UNITED STATES PATENT OFFICE

2,612,363

MINING APPARATUS

Arthur L. Lee, Upper Arlington, Ohio, assignor to
 The Jeffrey Manufacturing Company, a corporation of Ohio

Application January 23, 1946, Serial No. 642,862

11 Claims. (Cl. 262—30)

1

This invention relates to a mining machine and in the specific embodiment disclosed in detail and in its most specific aspect it relates to a mining machine of the shortwall type. It is to be understood, however, that a great many of the features, aspects, combinations and sub-combinations are applicable to different types of mining machines including, by way of illustration but not limitation, longwall, longwall-shortwall, or arcwall mining machines.

One object of my invention is to provide a mining machine with an improved gummer or cuttings removing mechanism, demountable in character, in which there is a power take-off provided on the mining machine, both while the demountable cuttings removing mechanism is in place and when it is removed.

It is another object of my invention to provide a mining machine with a gummer or cuttings removing mechanism which is either removable as a unit from the machine or is built into it as a permanent part and in which a pump unit including a pair of spaced rotating devices, having a throat between them, is provided to effect removal of the cuttings, the apparatus preferably being operable for reverse directions of travel of the cutter mechanism.

In carrying out the foregoing object, it is a further object of my invention to provide an improved cuttings guide means positioned to receive cuttings propelled by the spaced rotating devices or pump unit and to convey said cuttings to a mine conveyor, the discharge end of the guide means being mounted to translate and pivot with respect to the mine conveyor during operation of the mining machine.

A further and more specific object of the invention is to provide an improved means for connecting a cuttings directing guide means, chute, or conveyor to a second conveyor whereby said cuttings conveyor may translate and pivot with respect to the second conveyor.

It is yet another object of the invention to provide interlocking means between the gummer or cuttings removing mechanism of a mining machine, the cutter of which is reversible, and a reversing switch for the cutter driving motor, thereby insuring that the gummer or cuttings removing mechanism will always operate in the same direction for reverse operation of the driving motor.

It is still a further object of the invention to provide an improved, compact and highly efficient gummer or cuttings removing mechanism particularly adapted for a machine of the shortwall type.

2

Other objects of the invention will appear hereinafter, the novel features and combinations being set forth in the appended claims.

In the accompanying drawings,

5 Fig. 1 is a plan view of a shortwall type machine which incorporates features of my invention and wherein a portion of the machine is broken away to enhance the showing of the cuttings removing or gummer thereof, the cuttings guide means, chute, or conveyor being mounted upon a mine conveyor;

Fig. 2 is a side elevational view of a portion of the apparatus shown in Fig. 1;

15 Fig. 3 is a vertical sectional view of the rear portion of the machine taken substantially through the center thereof, showing particularly the machinery frame compartment and the gummer or cuttings removing mechanism, some parts being eliminated in the interest of clearness;

20 Fig. 4 is a rear end elevational view of the mining machine, with parts broken away and shown in vertical section;

Fig. 5 is a sectional plan view, with various 25 parts omitted, showing particularly the gummer or cuttings removing unit and its association with the cutter chain and cutter chain drive sprocket;

Fig. 6 is a sectional view of an electrical control portion of the machine showing operating 30 parts of electric control switches thereof, the view being taken on the line 6—6 of Fig. 7;

Fig. 7 is a vertical sectional view of the apparatus of Fig. 6, certain sections being taken 35 in different planes so as to illustrate all of the operating parts; and

Fig. 8 is an enlarged plan view of a detail of the machine which is shown in dotted lines in Fig. 1.

40 This application is a continuation in part of my application for a Mining Machine, Serial No. 586,979, filed April 6, 1945.

It is to be understood that, throughout, the disclosure of this application follows that of 45 my parent application above identified, unless a contrary fact is distinctly indicated in the drawings or specification.

Referring particularly to the drawings and to the shortwall machine which is therein disclosed and in which there is incorporated the 50 various combinations, sub-combinations, features and aspects of my invention, it may be pointed out first that one of the important considerations which dictates some of the structure is the over-all height of the mining machine.

55 Referring first to Figs. 1 and 2 of the draw-

ings, the machine includes a main frame 40 which in practice is preferably formed of two substantially independent frames including a forward motor frame or section 41 and a rearward machinery frame or section 42, the two frames or sections 41 and 42 being removably connected together as by machine screws or bolts. Removably attached to the rear end of the machinery frame or section 42 is a gummer or cuttings removing mechanism 43 which as hereininafter pointed out more completely is optionally employed or omitted.

Extending forwardly from the motor frame or section 41 is a kerf-cutting mechanism 44 including an elongated cutter bar 45 which is of substantially standard construction upon which there is mounted an endless cutter chain 46 provided with removable and reversible cutter bits 47. As is well known, the shortwall type of mining machine is adapted to be fed as a unit over the mine floor while cutting a kerf, the kerf being cut by first sumping the cutter bar into the solid coal and then feeding the machine laterally or across the coal face, all the while the kerf cutting mechanism 44 is in operation.

To effect the feeding of the mining machine as a unit, both at a kerf cutting speed and at a handling or higher speed and in reverse directions, the machine includes a pair of feed cable or rope drums 48 and 49 mounted on horizontal axes which are preferably in alignment, one on one side of the machine, the other on the other, as clearly illustrated in Fig. 1 of the drawings.

Drums 48 and 49 are provided with feed ropes or cables 50 and 51, respectively, which are adapted to be reeved about the sheaves of similar right and left hand rear sheave assemblies 52 and 53, respectively, and/or similar right and left hand front sheave assemblies 54 and 55, respectively.

Herein it need only be pointed out that the driving motor which drives the drums 48 and 49 tends to drive them always in the same direction, regardless of the direction of rotation of the motor, and that direction is such that it tends always to wind or pull in said ropes 50 and 51. That is, drum 48 tends always to be rotated by its driving motor in a clockwise direction, as viewed by a person facing it, and drum 49 tends always to rotate in a counterclockwise direction, as viewed by a person facing it.

In Fig. 1 of the drawings the machine is illustrated with the ropes 50 and 51 reeved about the pulleys 52 and 55 to effect a lateral feeding of the machine to the left, as viewed from the rear thereof, or upward, as viewed from the drawings. By the mere expedient of reeving rope 50 about the sheave of front assembly 54 and reeving rope 51 about the sheave of sheave assembly 53 and making the necessary operating adjustments on the machine, it may be fed to the right, reversely of that illustrated in said Fig. 1 of the drawings.

The shortwall mining machine illustrated is adapted to rest on and slide over the mine floor when in operation and the supporting surfaces of the machine are provided largely by four spaced hydraulic piston jacks or motors, those at the rear being designated 57 and those at the front being designated 58.

Attention is now directed particularly to Fig. 3 of the drawings and to some of the machinery or gearing which is contained within the machinery section 42 which includes the drive gearing leading to the cutter chain 46 and to the drums 48 and 49.

The drive mechanism leading to the drums 48

and 49 and the lubrication system for all of the machinery is described in detail in my parent application, above identified, and need not again be described here.

Extending from the motor section 41 into the machinery section 42 is the end of a hollow drive shaft 59 which is supported at its outer end on an anti-friction bearing 60 which in turn is supported on a web or integral bracket formed on the frame 42 which provides a substantially totally enclosing housing for the machinery or gears therein.

Keyed adjacent the end of the shaft 59 is a pinion 61 which meshes with a larger pinion 62 keyed to a shaft 63 having an integral bevel pinion 64, the shaft 63 being mounted in spaced bearings within the housing or frame 42. Pinion 64 meshes with a large bevel ring gear 65, the hub of which is mounted in a roller bearing 66 carried in a bearing cup in a removable top plate 67 which is removably attached to the frame 42 and forms a part of the enclosure or housing provided thereby. The hub of ring gear 65 is also mounted on spaced needle bearings 68 by which it is mounted for free rotation on a vertical or upstanding shaft 69, to the bottom of which a drive sprocket 70 for the cutter chain 46 is provided.

The drive shaft 69 extends through a hole in an elevated integral bottom plate 71 of the frame or section 42, which is preferably formed as a single steel casting, and is supported principally on a roller bearing 72 received in a removable cup 73 which is attached to the bottom plate 71 as by machine screws.

Since the sprocket 70 is, of course, exposed to the atmosphere and is outside the enclosure provided by the enclosing frame or section 42, within which enclosure there is a considerable amount of lubricating oil, though it is not filled with oil, oil seals are provided to prevent oil leakage.

From the above description it is evident that the shaft 69 is supported in the frame or section 42 by the bearing 72 at the bottom and by the combined actions of the top bearing 66 and the needle bearings 68 through the intermediary of the hub of ring gear 65. It is further evident from the above description that there is not a permanent or direct driving connection from the ring gear 65 to the shaft 69, but on the contrary the ring gear 65 is free to rotate on said shaft 69. To support the ring gear 65 on the shaft 69 against downward axial movement, there is a thrust ball bearing 81 interposed between a shoulder on the shaft 69 and the bottom of the hub of said gear 65.

Mounted concentric with the ring gear 65 and the shaft 69 and keyed onto the hub of said ring gear 65 is a bevel gear 82. Gears 65 and 82 therefore always rotate together and each is directly driven from the drive shaft 59 and always rotates with it.

At its bottom portion the gear 82 forms a driving portion of a jaw clutch and is provided with clutch dogs 83. Providing the driven portion of said clutch is a shiftable collar 84 having dogs adapted to be engaged with or disengaged from the dogs 83. Collar 84 is shiftable upwardly and downwardly on the shaft 69 and is splined or keyed thereto so that whenever it is driven, a driving relation is effected to said shaft 69. A bifurcated shipper 85 mounted on a rotary horizontal clutch shaft 86 is provided for operating the clutch 83-84, which clutch, obviously, is the clutch for effecting a driving or non-driving rela-

tion with the driving motor shaft 59 to the kerf cutter chain 46.

The operating shaft 86 is carried in appropriate bearings and is operatively connected to a transversely extending operating shaft (not shown) which extends through the upright side walls of the frame 42 and is provided with an operating lever and handle 91 on each side of the mining machine so that the clutch for engaging and disengaging the cutter chain 46 may be operated from either side of the machine.

Meshing with the bevel gear 82 is a bevel gear 92 mounted on a horizontal longitudinally extending shaft 93 provided with an integral power take-off head 94, thus providing a power take-off mechanism whereby the driving motor of the mining machine may be employed to drive a supporting truck in a manner well understood in the art, whenever the gummer or cuttings removing mechanism 43 is not attached to the machine. When said gummer or cuttings removing mechanism 43 is attached to the machine, it is provided with mechanism to derive power from the power take-off 94 and in turn is provided with an extended power take-off so as still to provide for the truck drive.

The shaft 93 is mounted on spaced anti-friction ball bearings, one of which is held in a receiving cup or socket 95 attached to and forming in fact a part of the enclosing frame or housing section 42. This recessed cup or socket 95 provides a protecting enclosure for the power take-off head 94 and prevents this continuously rotating part being freely exposed where it might harm an individual when rotating.

It is obvious that the head 94 is directly and permanently connected to the drive shaft 59 so that it always rotates with said shaft 59 and in a direction determined by the direction of rotation thereof. The power take-off head 94 includes a plurality of spaced bores or holes 96 adapted to receive coupling pins 97 of an associated power receiving mechanism which may be that for driving the supporting truck for the mining machine or, as illustrated in Fig. 3 of the drawings, coupling pins 97 provide a connecting means to the gummer or cuttings removing mechanism 43 by way of a drive shaft 98 mounted in spaced anti-friction ball bearings in the enclosing frame or casing 99 of the gummer 43.

The drive shaft 98 drives a bevel gear 100 which is in constant mesh with a pair of opposed and thus reversely driven bevel gears 101 and 102 (see Fig. 4), which are keyed to and drive reverse clutching sleeves 103 and 104, respectively, each mounted on a pair of spaced ball bearings which are carried by a driven shaft 105 which is in turn mounted on a pair of spaced ball bearings, one of which is seen at 106, said spaced ball bearings being supported on spaced brackets of the gummer frame 99.

Spined on the shaft 105 for sliding movement thereon is a driven clutch sleeve or member 107 which is provided with cooperating dogs on opposite sides or faces adapted to cooperate selectively with the clutch dogs of clutching sleeves 103 and 104. As clearly illustrated in Fig. 4 of the drawings, the clutch sleeve 107 is in its central or neutral position where the gummer is disengaged, but by shifting it in opposite directions the gummer may be driven in opposite directions relative to the direction of rotation of the motor shaft 59. It may be stated that in operation, the gummer is designed always to rotate in the same direction, but since the driving

motor that drives shaft 59 is reversible it is necessary to provide a reversing driving connection from the motor to the gummers. Furthermore, as hereinafter described more completely, there is an interlocking relation between the operating mechanism for the clutch 103, 104, 107 and the reversing switch for the driving motor, to insure that the gummer will always be driven in the proper direction.

- 10 To provide for the lateral shifting of the clutch member 107 or, in other words, its shifting along the axis of the shaft 105, a pivoted shipper 108 is employed which is mounted on a pivot shaft 109 carried in the gummer frame 99. 15 As illustrated in Fig. 3 of the drawings, the shipper 108 has an arm carrying arcuate plate 110 having a central detent cooperating with a centering spring-pressed ball 111, the function of which is to insure centering and thus disengaging of the clutch member 107 whenever the clutch operating mechanism is moved to its neutral position.

The two reversely rotating gears 101 and 102 mesh with a bevel gear 112 that includes a stub shaft that interfits with and is keyed to shaft 113. Shaft 113 is mounted on spaced ball bearings on a power take-off socket or receptacle 114 formed integral with the gummer casing 99. The shaft 113 is provided with a power take-off head 115 which is of generally similar construction to the head 94 and is of similar function. That is, it provides a power take-off by which a supporting truck for the mining machine may be driven whenever the gummer is attached to the mining machine. The gummer 43 is removable as a complete unit, by removing a plurality of machine screws 116 (see Figs. 4 and 5) which removably attach the gummer frame 99 to the frame 42. Obviously, the coupling provided by the power take-off head 94, pins 97 and shaft 98 provides a readily disconnectible driving connection from the shaft 93 to said shaft 98 of the gummer mechanism.

It may further be pointed out that there is a continuous or permanent drive between the shaft 59 and the power take-off 94 which, when the gummer is attached, also continues to the power take-off 115, and this gear train is uninterrupted by any clutches whatever so that when the gummer is attached the power take-off 115 always rotates with the motor shaft 59.

Reverting to a consideration of the operating structure of the gummer clutch, the shipper 108 is pivotally connected at its upper end (see Figs. 3 and 4), to a connecting box provided at the center of a spring centered shaft 120 carried in a laterally shiftable frame 121 to which an adjustable operating rod 122 is adjustably but rigidly connected. The spring held shaft 120 is normally held at a predetermined position with respect to the frame 121 by a pair of spaced centering springs 123 and consequently when the frame 121 is shifted to the right or left from its neutral or clutch disengaging position, as illustrated in Fig. 4, the operating shaft 120 will normally move with it to effect either of the reverse driving connections to the gummer shaft 105.

The dogs of the clutch members 103, 104 and 107 are preferably beveled and thus provide a safety throw-out mechanism in case of any overloading of the gummer and this safety throw-out mechanism is effected by compressing one of the springs 123 and thus moving the shaft 120 with respect to the frame 121, even though said frame

121 is held in either of the clutch engaging positions.

The operating rod 122 is pivotally connected to a pivoted gummer clutch operating lever 124 (see Figs. 1 and 4), which is provided with a spring-pressed ball or pin adapted to cooperate with any one of three dents in a dent plate 125 and thus frictionally hold the operating lever 124 in its clutch disengaging position or either of its reverse clutch engaging positions. There is an interlock mechanism also connected to the pivoted lever 124 which is described in detail hereinafter and which provides an interlock between said lever and the reversing switch of the driving motor of the mining machine.

The previously described shaft 105 drives a pair of reversely rotating sweeping, conveying, pumping or feeding devices which are laterally spaced apart and substantially equidistant on opposite sides of the longitudinal central axis of the machine, the two sweeping devices being of similar construction, one of them being shown in section in Fig. 4 of the drawings, the other being partly shown in elevation therein. Likewise, in Fig. 5 of the drawings, one of these devices is shown in section and the other in plan.

Since the two sweeping devices are similar, a detailed description of one will apply to both and similar reference characters are employed for the detailed parts. For identification purposes the one on the right, as viewed from the rear of the machine, is designated 126 and the one on the left 127. Each sweeping device 126, 127 is driven from shaft 105 by a bevel gear 128 keyed to the end thereof which meshes with a similar bevel gear 129 keyed to an upright shaft 130 journaled in spaced anti-friction bearings on appropriate portions of the frame 99 of the gummer 43.

At its lower end the shaft 130 is provided with an integral disc-shaped head 131 which is the head or top plate of a sweeping mechanism 126 or 127, as the case may be. Extending downwardly from each head 131 is a cylinder or drum 132 which is preferably open at the bottom and the axis of which is substantially along the axis of the shaft 130 and is vertical.

The gummer frame 99 includes a bottom plate 133 which at the back is provided with an upwardly curved edge and which at the front terminates just behind the path of travel of the cutter bits 47. Extending upwardly from and rigidly attached to the bottom plate 133 is a post or shaft 134 for each of the sweeping devices 126 and 127, the axis of the post or shaft 134 being eccentric with respect to the axis of the drum 132 and shaft 130. Mounted for free rotation on each post or shaft 134 is a plurality of blades 135, each provided with an integral bracket 136 which provides the aforesaid pivotal connection to the pin or post 134.

The periphery of each drum 132 is provided with a plurality of vertical slots 137, there being one for each blade 135. A blade 135 projects through each of the slots 137 and as the drums 132 rotate, for example, in the direction of the arrows as seen in Fig. 5 of the drawings, it is evident that each blade will have a combination rotating motion with respect to the bottom plate 133 and a reciprocating motion with respect to the drum 132, the latter being, of course, due to the eccentric relation between the axis of the drum 132 and the post 134.

It is thus evident that by rotating the two drums 132 of the sweeping mechanism 126 and 127 so that sweeping mechanism 126 rotates counter-clockwise and sweeping mechanism 127

rotates clockwise, as viewed in Fig. 5 of the drawings, the cuttings which are delivered to the rear of the machine by the cutter chain 46 and bits 47 will be swept through the throat formed between the two sweeping devices by the combination rotating and reciprocating blades 135 and be swept, conveyed, pushed, pumped, or impelled out of the rear of the gummer or of the mining machine and thus entirely out of its path of travel.

As best seen in Fig. 5 of the drawings, a longitudinal axis through the mining machine will pass down the center of the machine through the shaft 69 and the cuttings will be guided into the paths of the blades 135 by guide members 138 which are formed rigid with the gummer frame 99 and act to direct the cuttings into the path of the sweeping mechanisms 126 and 127. Guide members 138 are provided with slots 139 in their outer upright plates so that the gummer may be slid forwardly and guided into place, with a pin 140 being received by each slot 139, the two pins 140 on opposite sides of the machine being rigidly attached to an upright partition of the frame member 42.

As clearly illustrated also in Fig. 5 of the drawings, each blade 135 reciprocates relative to its associated drum 132 between maximum and minimum extensions beyond the face of the drum, the minimum extension being when the plate has just passed its rearmost position relative to the gummer 43. The maximum position of the blade 135 is substantially that illustrated for the forwardly extending blade 135 of the sweeping mechanism 127 and this, of course, occurs when the central vertical plane of the blade passes through the axes of the post 134 and the shaft 130.

It is further evident by reference to Fig. 5 that the blades of the sweeping devices 126 and 127 are staggered; that is, a blade 135 of each sweeping device 126 and 127 is positioned substantially midway between two blades of the other so that blades 135 of the sweeping devices 126 and 127 successively sweep over the central or sweeping pathway between the drums of the sweeping devices 126 and 127. Because of this fact, they can overlap or, in other words, sweep over at least some common portion of the plate 133.

As previously mentioned, the sweeping devices 126 and 127 are always intended to rotate in the same directions so as to sweep the cuttings by positive action from the front to the rear, as indicated by the arrows in Fig. 5. This gummer, however, acts with equal facility regardless of the direction of rotation of the chain 46 and the bits 47. In Fig. 5 arrows indicate a counterclockwise rotation of the drive sprocket 70. However, in operation the bits 47 may be reversed and the chain 46 likewise reversed whenever the lateral feeding direction of the mining machine is changed.

Obviously, due to the symmetrical arrangement of the gummer, including the guide members 138, it will operate with equal facility regardless of the direction of rotation of the sprocket 70 and the direction of travel of the cutter chain 46. Since the same motor drives both the sprocket 70 and the gummer, it is, of course, necessary to provide the gummer reversing clutch 103, 104, 107, above described, and interlocking mechanism, hereinafter described, is provided to insure that the gummer sweeping devices 126 and 127 will always rotate in the proper direction.

It may be further pointed out that as the tension and slack runs of the cutter chain 46 travel rearwardly along the bottom of the mining ma-

chine, as described more completely hereinafter, the cuttings will be guided largely by a pair of similar guide ribs 141. These ribs 141 are actually integral parts of the frame sections 41 and 42 and the parts integral with each of said sections 41 and 42 act as continuations of the parts of the other. As a matter of fact, reverting to Fig. 5, the portions of the frame 42 to which the pins 140 are connected, are parts of the guide ribs 141, as there indicated.

As was previously mentioned, an interlock is provided between the reversing switch of the motor 154 and the gummer 43 to insure that said gummer will always discharge the cuttings rearwardly through its central throat for reverse operation of said motor. Figs. 6 and 7 show certain portions of the motor control and reversing mechanism which suffice for an understanding of the operation thereof and the above mentioned interlock.

Mounted in an appropriate compartment on the rear right hand side of the motor section 41 is a motor reversing drum 416 which is provided with an operating shaft 417 and reversing lever 418. Positioned below the drum 416 is a motor switch 419 provided with an operating cam 420 which may be operated from one side of the machine by a switch lever 421 and shaft 422, or from the opposite side of the machine by a similarly located lever which is connected by way of a cross-rod 423 which in turn is connected to the shaft 422 by a linkage mechanism 424.

Carried by the shaft 422 is a swinging arm 425 which extends into an opening of a latch pin 426 which extends slightly through a guide 427 carried on a switch mounting plate 428. The latch pin 426 cooperates with a cam 429 which is attached rigidly with the shaft 417 and it prevents rotation of said shaft 417 and thus prevents operation of the reversing drum 416, except when the motor switch cam 420 is swung to motor switch opening position, in which case the latch pin 426 is moved out of the path of the cam 429 and permits it to be moved to a reverse position.

Also mounted on the drum operating shaft 417 is an upwardly extending arm 430 which at its upper end carries a roller 431 received in an elongated opening in an operating clip 432 which is carried on a transversely extending rod 433 which extends to the opposite side of the machine and is operated by a lever generally similar in position and construction to lever 418.

Also extending through the wall or plate through which shafts 417 and 422 extend, there is an operating shaft 434 which on its inner end carries a rigidly attached downwardly extending arm 435 which is bifurcated at its bottom and extends about a roller 436 mounted on a pivot pin carried by the arm 430. Outside said casing the shaft 434 is provided with a rigidly attached lever 437 connected to a transversely extending rod 438 (see Figs. 1, 3, 7 and 8) of the interlock mechanism between the reversing switch including drum 416, and the gummer 43.

It is obvious that if the operating shaft 417 is rotated to one position to cause rotation of the motor 154 in one direction, the rod 438 will be shifted to one position through the interconnection provided by arm 430, roller 436, arm 435, shaft 434 and lever 437. If the motor reversing switch is moved to a reverse direction by rotation of the shaft 417, a responsive swinging movement of the lever 437 will take place to shift the rod 438.

Referring particularly to Figs. 1 and 8 of the

drawings, it will be seen that connected to the gummer clutch controlling lever 124 is an arm 439 to which is pivotally attached an interlocking rod 440. Shifting of the lever 124 will, of course, reciprocate the rod 440 and shifting of the switch operating rod 417 and the switch reversing drum 416 will reciprocate the rod 438.

In Fig. 8 of the drawings, the rods 438 and 440 are shown in the positions which they will have when the clutch operating lever 124 is in its neutral position and the reversing switch lever 417 is in one of its reverse operating positions.

With the rod 438 in this one position, it is only possible to move the gummer clutch lever 124 in a clockwise position as this is permitted by a notch 441 in rod 438 into which one projection of a U-shaped yoke 442 may freely extend. Reverse operation of the lever 124 from its neutral position is prevented, for if attempted the left hand arm of yoke 442 would contact the adjacent side of rod 438 and prevent such clutch engaging movement. On the other hand, if the motor switch is reversed, this will produce upward movement of the rod 438 from the position illustrated in Fig. 8, whereupon a notch 443 thereof will only permit counterclockwise or reverse movement of the clutch operating lever 124 from the neutral position.

Furthermore, the interlock provided by the structure of Fig. 8 will prevent reversal of the motor reversing switch 416, 417 except when the gummer clutch is in its neutral position, for when said gummer clutch is in either of its operating positions, there will be one arm of the yoke 442 received in a notch 441 or 443 which will lock the rod 438 and thus lock said motor reversing switch in position.

From the above description, it is evident that the disclosed machine is of low overall height and thus meets requirements of thin seam mining. Furthermore, the machine is one which meets the requirements of conveyor mining, particularly wherein a face conveyor is employed directly behind the mining machine. The controls for the machine are located on the sides and are substantially duplicated on each side. The location of the controls at the sides is also desirable, particularly where the gummer or cuttings remover is attached and this device may either be attached or detached, or, in other words, the machine may be built with or without it and if built with it, it may be subsequently removed.

Interlock mechanism is provided so that the gummer or cuttings remover will always discharge cuttings to the rear, regardless of the direction of rotation of the motor or of the cutter chain. Since the machine is designed to cut by movement either to the right or to the left, this is an important feature.

The gummer or cuttings removing device acts to gather cuttings delivered to the rear of the machine by the cutter chain 46 and to convey said cuttings rearwardly with equal facility for reverse directions of travel of said cutter chain. This gummer acts to convey the cuttings rearwardly through a restricted throat by positive or pumping action; thus it will create a force or pressure sufficient to impel or move the material rearwardly from the machine.

Referring again to Figs. 1 and 2, an important part of my invention resides in the cuttings removal mechanism for conveying cuttings from the mining machine and discharging them into a mine conveyor for removal from the mine. In the embodiment of my invention illustrated, the

cuttings conveyor mechanism includes a funnel or material directing chute 150 that is secured to upright members 151 which are formed as an integral part of the bottom plate 133 of the gummer or cuttings removal mechanism.

The funnel or material directing chute 150 is formed to include a rearwardly extending lip 152 to which a generally horizontally extending flexible tube, conduit or cuttings directing guide 153 of a follower conveyor 155 is secured. The flexible tube 153 may be formed of any suitable material and in any suitable manner, but herein I have shown it as being formed of a resilient corrugated material which is reinforced by a helical metal coil 154 which causes it to retain its shape. The rear or discharge end of the tube 153 of the follower conveyor 155 is mounted upon a truck or rack 156 which in turn is mounted upon and follows or translates along a mine conveyor 157 during operation of the mining machine. While the truck or rack 156 of the follower conveyor 155 may be secured to the mine conveyor in any suitable manner to translate therealong, I preferably form the side walls 158 of the mine conveyor 157 to include a pair of outwardly extending lips or flanges 159 one of which extends along each side and throughout the length thereof. These flanges are adapted to receive rollers 160 and 161 of the truck or rack 156.

The truck or rack 156 includes a bed plate or slide 162 from which a bar or beam 163 extends across the open top of the mine conveyor and upon the end of which is mounted the roller 160. Roller 160 is a double flanged spool that fits and rolls along a lip 159 of the mine conveyor. The bed plate or slide 162 rides upon the upper surface of the other lip 159 of the mine conveyor and carries a pair of spaced rollers in the form of single flanged spools 161 which are adapted to engage a lip 159 of the conveyor, as hereinafter described. A ring or mount 164 on the end of the tube 153 is secured to the top of the bed plate 162 and centrally thereof.

In operation, the bed plate or slide 162 rests upon a top edge of the mine conveyor and is retained thereon by the pull of the flexible tube 153 and the roller 160 on the end of the bar or beam 163 which engages the lip 159 over which the bar 163 extends. The mining machine in cutting a kerf moves substantially parallel to the mine conveyor and pulls or causes the follower conveyor 155 to translate along the mine conveyor 157. The rollers 161 engage the adjacent flanges 159 of the mine conveyor to limit the pivotal movement of the truck or rack 156 about the roller 160 and to secure the truck to the mine conveyor.

The cuttings that are ejected from the mining machine by the gummer or cuttings removing mechanism are thrown, forced or pumped rearwardly through the tube 153 of the follower conveyor and are deposited in the mine conveyor 157. The tube 153 may be comprised of two or more sections joined together to accommodate it to various mining conditions and positions of the mine conveyor with respect to the mining machine. The internal diameter of the tube 153 also preferably tapers or progressively increases outwardly slightly from the mining machine to prevent material from becoming packed therein.

In the past, the practice prevalent in disposing of the cuttings from such mining machines was to station a miner adjacent the exhaust port of the machine to shovel the cuttings out of the

path of the mining operations, and from the foregoing it will be seen that I have provided an improved cuttings directing mechanism that connects the cuttings removing means of the mining machine with a mine conveyor for directing and conveying the cuttings propelled from the positive acting cuttings pumping mechanism. The mechanism is of extremely simple construction and requires little or no attention from the mining machine operator since the truck or rack 156 follows the mine conveyor 157 and is moved or pulled therealong by the mining machine.

The follower conveyor is readily removed from the mine conveyor without the use of tools by pivoting the bed plate 162 about the roller 160 until the roller 161 becomes disengaged sufficiently from the flange 159 that it is adapted to engage and then by moving the follower conveyor to disengage the roller 160 from the flange 159 with which it is associated and then lifting the follower conveyor upwardly from the mine conveyor. It will be seen that the follower conveyor may be installed upon the mine conveyor from either side thereof since the mine conveyor is symmetrical in cross section.

Obviously those skilled in the art may make various changes in the details and arrangement of parts without departing from the spirit and scope of the invention as defined by the claims hereto appended, and I therefore wish not to be restricted to the precise construction herein disclosed.

Having thus described and shown an embodiment of my invention, what I desire to secure by Letters Patent of the United States is:

1. In a mining machine, the combination with a frame, of a reversible motor mounted thereon, kerf cutting mechanism connected to said frame including an endless cutter chain and drive sprocket, cuttings removing mechanism located adjacent said cutter chain and drive sprocket including a pair of laterally spaced rotating drums having blades which reciprocate relative to said drums and sweep the cuttings rearwardly, reversing gearing interconnecting said reversible motor and said cuttings removing mechanism to drive it including reversing gearing whereby said cuttings removing mechanism will always be driven in the same direction for reverse directions of rotation of said motor, reversing switch mechanism for reversing the direction of rotation of said motor, and interlocking mechanism between said motor reversing mechanism and said cuttings removing mechanism reversing gearing to require that the cuttings removing mechanism be always driven in the same direction, as aforesaid.

2. In a mining machine, the combination with a frame, of a reversible motor mounted thereon, kerf cutting mechanism connected to said frame including an endless cutter chain and drive sprocket, cuttings removing mechanism located adjacent said cutter chain and drive sprocket, reversing gearing interconnecting said reversible motor and said cuttings removing mechanism to drive it including reversing gearing whereby said cuttings removing mechanism will always be driven in the same direction for reverse directions of rotation of said motor, reversing switch mechanism for reversing the direction of rotation of said motor, and interlocking mechanism between said motor reversing mechanism and said cuttings removing mechanism reversing gearing to require that the cuttings removing mechanism

be always driven in the same direction, as aforesaid.

3. In a mining machine, the combination with a reversible motor, reversible control mechanism for said motor, a driven cuttings removing member adapted to be driven in one direction only, gearing interconnecting said motor and driven cuttings removing member including reversing gearing, reverse operating means for said reverse gearing, means interlocking said reversible motor control mechanism and said reverse operating means whereby said driven cuttings removing member is always driven in the same direction when operated, said interlocking means including a rod having spaced notches on opposite sides and operated by said reversible control mechanism, and a cooperating forked member connected to said reverse operating means for said reversing gear, said forked member fitting said notched rod and being insertable selectively into said spaced notches by reverse movements thereof.

4. In a mining machine, the combination with a reversible motor, reversible control mechanism for said motor, a driven member adapted to be driven in one direction only, gearing interconnecting said motor and driven member including reversing gearing, reverse operating means for said reverse gearing, means interlocking said reversible motor control mechanism and said reverse operating means whereby said driven member is always driven in the same direction when operated, said interlocking means including a rod having spaced notches on opposite sides and operated by said reversible control mechanism, and a cooperating forked member connected to said reverse operating means for said reversing gear, said forked member fitting said notched rod and being insertable selectively into said spaced notches by reverse movements thereof.

5. In a mining machine, the combination with a reversible motor, reversible control mechanism for said motor, a driven cuttings removing member adapted to be driven in one direction only, gearing interconnecting said motor and driven cuttings removing member including reversing gearing, reverse operating means for said reverse gearing, and means interlocking said reversible motor control mechanism and said reverse operating means whereby said driven cuttings removing member is always driven in the same direction when operated.

6. In a mining machine, the combination with a reversible motor, reversible control mechanism for said motor, a driven member adapted to be driven in one direction only, gearing interconnecting said motor and driven member including reversing gearing, reverse operating means for said reverse gearing, and means interlocking said reversible motor control mechanism and said reverse operating means whereby said driven member is always driven in the same direction when operated.

7. In a mining machine, the combination with a frame, of an endless kerf cutting chain mechanism mounted to run on said frame, a sprocket for driving said chain, a removable cuttings removing attachment positioned adjacent said sprocket and chain for removing cuttings from said frame, said attachment including a pair of spaced rotatable devices constructed and arranged to gather cuttings from said chain as it travels around said sprocket and convey the cuttings between said devices and eject them from said machine, and spaced cuttings guides on said

frame adapted to guide cuttings to said rotatable devices, said guides also cooperating with said frame to guide said attachment into position for attachment thereto.

8. In a mining machine, the combination with a frame, of an endless kerf cutting chain mechanism mounted to run on said frame, a sprocket for driving said chain, means positioned adjacent said sprocket and chain for removing cuttings from said frame, said means including a pair of spaced rotatable devices constructed and arranged to gather cuttings from said chain as it travels around said sprocket and convey the cuttings between said devices, a flexible tubular guide means disposed to receive cuttings from between said rotatable devices, and carriage means supporting the discharge end of said guide means and mounted to follow a mine conveyor whereby said guide means translates along and discharges cuttings into said mine conveyor during operation of the mining machine.

9. In a mining machine, the combination with a frame, of an endless kerf cutting chain mechanism mounted to run on said frame, a sprocket for driving said chain, means positioned adjacent said sprocket and chain for removing cuttings from said frame, said means including a pair of spaced rotatable devices constructed and arranged to gather cuttings from said chain as it travels around said sprocket and convey the cuttings between said devices, a guide means disposed to receive cuttings from between said rotatable devices, a mine conveyer, and truck means pivotally mounting the discharge end of said guide means on said mine conveyer and riding said mine conveyor whereby the discharge end of said guide means may translate along said mine conveyor and pivot with respect thereto during operation of the mining machine.

10. In a mining machine, the combination with a frame, of an endless kerf cutting chain mechanism mounted to run on said frame, a sprocket for driving said chain, means positioned adjacent said sprocket and chain for removing cuttings from said frame, said means including a pair of spaced rotatable devices constructed and arranged to gather cuttings from said chain as it travels around said sprocket and convey the cuttings between said devices, a resilient longitudinally extendable tubular guide means disposed to receive cuttings from between said rotatable devices, a mine conveyer, and truck means pivotally mounting the discharge end of said guide means on said mine conveyer and riding said mine conveyor whereby the discharge end of said guide means may translate along said mine conveyor and pivot with respect thereto during operation of the mining machine.

11. In apparatus of the class described, a cuttings removing mechanism including a pump mechanism constructed and arranged to gather cuttings from a kerf cutter, a tapered longitudinally extendable cuttings guide tube arranged to receive cuttings pumped by said pump mechanism and direct and discharge said cuttings into a mine conveyor as conveyed solely by said pump mechanism, and truck means pivotally mounting the discharge end of said guide tube on said mine conveyor and riding said mine conveyor whereby said guide tube may translate along and pivot with respect to said mine conveyor as said kerf cutter cuts a kerf.
